UNITED STATES PATENT OFFICE

WILLIAM W. MACFARLANE, OF ELMINS PARK, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRAIN-CONTROL SYSTEM

Application filed May 4, 1916, Serial No. 280,194. Renewed March 1, 1919.

This invention relates to train controlling systems and more particularly to those systems in which train-carried controlling devices are automatically controlled by track conditions.

The principal object of the invention is to provide a simplified method for utilizing track circuits to continuously control a train moving in either direction without the use of ramp rails or continuous contact rails other than the traffic rails themselves. The present invention embodies train controlling devices of the same general type as are disclosed in my copending application Serial No. 82,861, filed March 8, 1916.

Another feature of the invention is the provision of an automatic brake operating mechanism in which a timing device prevents the immediate application of the brakes upon the receipt of a danger signal thereby giving the engineer an opportunity to bring the train to a stop through means directly under his control.

Another feature is the employment of means controlled by the presence of a train in a block for supplying current to the rails of the block to control the train.

Still another feature is the provision of speed controlled devices to permit a train to creep into a train-occupied block at a very low speed, and to prevent the train from exceeding a predetermined maximum speed regardless of track conditions.

In order to control the operation of the train governing apparatus a track circuit system particularly adapted for use on a single track railway is preferably employed. In addition to the ordinary normally closed track circuit in each block other normally open circuits are employed which are adapted to furnish to the rails of the block a train controlling current of a different character than that supplied by the normally closed circuit. Either alternating or direct current may be used in both the normally open and the normally closed circuits providing the current in the different circuits be made to distinguish by some characteristic of phase, frequency, voltage or the like. Preferably, however, alternating current is em-

ployed for the normally closed circuit and direct current for the normally open train controlling circuits.

In the drawings in which like reference characters designate corresponding parts:

Figure 1 is a general diagrammatic view 55 of a track circuit system embodying part of the invention.

Figure 2 is a diagrammatic view of a train 60 controlling system embodying another part of the invention.

Figure 3 is a longitudinal section taken on the line 3—3 of Figure 4 showing the valve 65 operating mechanism.

Figure 4 is a view partly in section and 70 partly in elevation of the brake mechanism taken along the line 4—4 of Figure 3.

In the track circuit system illustrated in Figure 1 of the drawings, the track rails 1 and 2 are divided into suitable block sections 75 A, B, C, D and E which are insulated from each other in the usual manner. In the form shown each block has normally impressed thereon an alternating current supplied by the transformer 3 connected across the line 75 conductors 4 and 5. The supply conductors 6 and 7 connect the secondary of the transformer to the rails at points near the middle of the block section. A non-inductive resistance 8 is preferably interposed in the conductor 6 to prevent an excessive flow of current from the transformer when a train is bridging the rails near the points of connection of the supply conductors 6 and 7 therewith.

Each block section is provided with two 85 alternating current track relays 9 and 10 connected to the rails at the ends of the block through the conductors 11—12 and 33—34 respectively and adapted to be normally energized by current from the transformer 3 when the block is not occupied by a train, in a manner well-known in the signaling art. These track relays are preferably of the type 90 which will respond only to a given frequency 95 which, of course, will be that characteristic of the current supplied by the transformer 3, and will therefore be immune to direct current or to alternating current of a different frequency from that in connection with

which they are designed to operate. If found desirable, some form of condenser might be provided in the connection between each alternating current relay and the track to prevent direct current from interfering with these relays.

The track rails of each block have also connected thereto at opposite ends of the block, the sources of direct current 13 and 14 which supply current for controlling suitable train governing devices preferably mounted on the locomotive of the train and arranged to take current from the rail through contact shoes having direct engagement therewith. The current sources 13 and 14 are preferably designed to furnish a current of comparatively low voltage and relatively large volume.

The source 13 is connected to the track rail 1 through the conductor 15 and to the track rail 2 through the conductor 16, contacts 17, conductor 18, contacts 19, and conductor 20 including the resistance 21, to the rail 2. The contacts 17 are adapted to be bridged by the circuit closer 22 which is adapted to be held out of engagement with the contacts when the track relay 9 is energized. When the relay 9 is deenergized, as by the short-circuiting effect of a train in the block, the circuit closer 22 is moved by the action of gravity into engagement with the contacts 17. Normally the circuit including the source 13 is open at the contacts 17 and is closed at this point coincidently with the entrance of a train into the block and upon the consequent deenergization of the track relay 9.

The contacts 19 in the circuit through the source 13 are normally held closed by a circuit closer 24 controlled by the track relay 10 of the adjacent end of the adjoining block. The action of gravity will move the circuit closer 24 out of bridging engagement with the contacts 19 upon the deenergization of the relay 10 caused by the presence of a train in the corresponding block. Thus, under normal conditions, that is, when no train is in either of two adjacent blocks, the circuit through the source 13 of one block is open at the contacts 17 and closed at the contacts 19.

At the other end of each block the source of current 14 is connected through the conductor 26 to the track rail 1 and through the conductor 27, contacts 28, conductor 29, contacts 30, and conductor 31 including the resistance 32 to the track rail 2. The contacts 28 are adapted to be bridged by the circuit closer 22 when the relay 9 of the adjacent end of the adjoining block is energized, while the contacts 30 are adapted to be bridged by the circuit closer 24 when the track relay 10 is deenergized.

It will be apparent that, when the insulated blocks on both sides of any given block are unoccupied by a train, the contacts of the train control circuits of the given block which

are under the control of the relays in the adjacent blocks will be closed. Consequently a train which may be present in the given block will have current supplied to its controlling device by the closed control circuit at the end of the block which it is approaching, since the contacts of the control circuits which are governed by the train-occupied block are also closed because of the deenergization of the track relays 9 and 10.

The current supplied by the circuit at the rear of the train will have no effect on the control mechanism 35 carried by the locomotive because of the shunting effect of the wheels and axles of the train which are between the contact shoes 36 and 37 and the source at the rear. It will be clear, therefore, that a train entering the block to the rear will in no way affect the progress of the train in the block ahead but will itself be stopped because of its inability to take current from the circuit at the forward end of the block since this circuit will of course be open at the break controlled by the train in the block ahead. Consequently, when two trains are proceeding along the track in the same direction the forward train will not have its progress restricted by the presence of the train in the rear, while, on the other hand, the train to the rear cannot advance into the block immediately to the rear of the one occupied by the forward train. There must always be, then, in the track circuit system disclosed, an intervening clear block between two trains traveling in the same direction so that a following train can by no possibility approach near enough to the train in advance to be in danger of participating in a rear-end collision therewith.

In the case where two trains are approaching each other on a single track, since the train in an occupied block opens a break in the train control circuit of block ahead, it will be clear that the approaching train will be stopped as soon as it enters the block ahead of the first train. It will be clear also that, since the second train opens the train control circuit in the adjacent end of the block ahead of it, that the first train will also be stopped as soon as it enters the block ahead of the second train.

Therefore, not only will a train approaching from the rear be stopped when it reaches the block immediately to the rear of the train-occupied block, but also both of the approaching trains will be stopped immediately upon the entrance of either train into the block immediately ahead of the other train. The result of this is that no train can approach nearer than a block to another train regardless of whether the other train is running toward or away from the first train or is not moving at all. Also of two trains running in the same direction, the following train will be prevented from approaching

within dangerous proximity to the train ahead, while the train in advance, which is constantly tending to withdraw from what might become a dangerous position, will have no restriction whatever placed upon its movement by the approach of the following train. It will accordingly be obvious that each train as it travels creates and carries with it a protective zone which extends through the block immediately to the rear and the block immediately ahead of the train-occupied block, and which thereby serves to prevent the approach of two trains to a position within a block-length of each other.

15 In Figure 2 of the drawings is shown a preferred embodiment of a system of train control which is adapted to be utilized in connection with the track circuit system already described.

20 At 35 is shown the train controlling relay which, through the contact shoes, 36 and 37, is in continuous bridging engagement with the track rails 1 and 2. As in the device disclosed in the copending application to which reference has been made, this rail bridging current path is constructed to offer an extremely low resistance to the passage of current therethrough, so that sufficient current will be diverted from the paths formed by 25 the wheels and axles to operate the relay 35. The coil of the relay preferably consists of a helical strip of copper, or other highly conductive material, having a comparatively large cross-sectional area. The ends of the 30 coil are connected to massive copper cables 38 which lead to and are embedded in the contact shoes 36 and 37. The combined resistance of the coil of the relay 35, the cables 38 and the contact shoes 36 and 37 is so low 35 that the adjacent wheels and axles are short-circuited and substantially the entire current flow from rail to rail takes the path of least resistance through the control relay 35.

40 The armature 39 of the relay is adapted to be held in engagement with the contact plate 40 in the normally energized condition of the relay. A stop 41 is provided against which the armature is biased by gravity when current is not flowing through the relay. The contact plate 40 is engaged by the armature 45 to close the main control circuit which includes the battery 42, conductor 43, conductor 44, armature 39, contact plate 40, conductor 45, relay 46, and conductor 47 back to battery. The relay 46 is thus energized to hold the members 48 and 49 of its double armature against the front contacts 50 and 51 thereby closing circuits through the green, or safety, lamp 52, and also through the 55 brake controlling magnet 53.

60 The circuit through the safety lamp 52 includes the battery 42, conductor 43, conductor 44, conductor 54, armature 48 of relay 46, front contact 50, conductor 55, safety lamp 52, conductor 56, and conductor 47 back to

battery. Current to energize the brake magnet 53 flows over a shunt circuit from the conductor 54, to armature 49, front contact 51, conductor 57, conductor 73, magnet 53, conductor 74, and conductor 47.

Upon the deenergization of the control relay 35 due to danger conditions, the armature 39 will break contact with the contact plate 40 whereupon the relay 46 will drop its double armature to break the circuits through the safety lamp 52 at the front contact 50 and through the brake magnet at the front contact 51. The deenergization of the magnet 53 will set the brake operating mechanism into action. Simultaneously with this the red, or danger, lamp 89 will be lighted and the bell 90 actuated by means of current supplied from the battery 42, conductor 43, conductor 44, conductor 54, armature 49, back contact 91, conductor 92, conductor 93, lamp 89, conductor 94 to common return conductor 47, and also from conductor 93, to bell 90, conductor 95, and conductor 94 to common return conductor 47 back to battery. Thus, upon the entrance of a train into a danger zone, danger signals will be actuated in the cab and a brake actuating mechanism will be set into operation.

65 The brake magnet 53, to which reference has been made, is adapted to control a valve operating mechanism through the connection of the plunger core 58 with the lever 59 pivoted to a stationary support at 60. The valve stem 61, carrying the valves 62 and 63, is adapted to be held in an elevated position by 70 the lever 59 when the magnet 53 is energized. The valve 62 cooperates with a valve seat 64 to control the flow of air from the train pipe 65 through the pipe 66 to the cylinder 67. A piston 68 in the cylinder 67 is connected 75 through the piston rod 69 with the stem 70 of a brake valve 71 adapted to control an exhaust port in the train pipe 65.

80 In order to retard to some extent the action of the automatic brake actuating mechanism so as to give the engineer time to slow down his train through the manual control, as well as to allow the train to pass over a dead section at a cross-over, or the like, the regulating chamber 72 is provided.

85 This regulating chamber consists of a cylinder 75 in which is mounted a piston 76 the position of which is adapted to be adjusted by means of the screw-threaded stem 77. A lock nut 78 is adapted to lock the screw in a fixed position. A cap 79 closes the end of the cylinder and serves as a nut through which the threaded stem 77 can be manipulated. The cap is preferably detachably mounted on the end of the cylinder in any suitable manner as by means of the bayonet joint indicated at 80 in Figures 3 and 4. The cylinder 75 is in constant communication with the valve chamber 81 and cylinder 67 through the passage 82.

The regulating, or timing, cylinder 75 is preferably of such a size that an appreciable interval of time will be required to supply sufficient air thereto through the comparatively small aperture 83 to raise the pressure in the chamber 72 and cylinder 67 to the point necessary for the operation of the piston 68. The extent of the time interval may be regulated by varying the position of the piston 76 to thereby change the volume of the chamber 72, as will be evident.

In order to prevent the complete exhaustion of pressure from the train pipe following an action of the automatic brake controlling mechanism, a spring 84 is mounted on the valve stem 69 and bears against a collar 85 thereon to move the piston to inoperative position when the pressure in the brake pipe and chamber 72 is lowered to a certain predetermined minimum. The degree of pressure exerted by the spring 84 may be varied through moving the slideable abutment member 86 by means of the adjusting screw 87. Locking bolts 88 are preferably provided for fixing the position of the abutment member when the adjustment has been made.

Provision is made by means of the speed controlled device 96 for allowing a movement of the train under greatly reduced speed when danger conditions exist so that, for example, a train might creep forward into a block occupied by a disabled train for the purpose of giving assistance. The speed controlled device is of the same type as that shown in the companion case in which a frangible bulb 97 containing mercury 98 is caused to rotate through a mechanical connection with a moving part, such as an axle of the train. Contacts 99, bridged by the mercury under a very low speed, such as two or four miles an hour, are adapted to be electrically disconnected by the action of centrifugal force on the mercury upon an increase of speed above the figure named. Under the minimum speed referred to a circuit is established through the brake control magnet 53 as follows: battery 42, conductor 43, conductor 44, conductor 100, contacts 99 and mercury 98, conductor 73, brake magnet 53, conductor 74, and common return conductor 47 back to battery.

Current flowing over the circuit just traced will hold the magnet 53 energized or will re-energize it, if the speed of the train has been lowered to the permissible rate due to an operation of the automatic brake actuating mechanism. The energized magnet 53 will lift the valve 62 to its seat and lift the valve 63 off its seat in the exhaust port 101 to vent the regulating chamber 72 and cylinder 67 to permit the spring 84 to withdraw the piston 68 from valve operating position.

A supplemental speed controlled device is shown at 102 which is similar in construction to the speed controlled device 96 already described. In the speed controlled device

102 however, the contacts are arranged to be disengaged by the mercury only when the vehicle exceeds the predetermined maximum speed at which it is permitted to travel. Under such conditions the magnet 103 in the conductor 104 will be deenergized to open the supplemental brake valve 105 and vent the train pipe to apply the brakes. This operation will take place regardless of the traffic conditions, so that the vehicle cannot exceed the maximum allowable speed even under safety conditions.

What is claimed, is:

1. A system of train control comprising: a track divided into insulated blocks, means controlled by the presence of a train in a block to supply current to the rails of the block, and means on the train for short-circuiting the wheels and axles thereof and utilizing current from said rails to control the train.

2. A system of train control comprising: a track divided into insulated blocks, means controlled by the presence of a train in a block to supply current to the rails of the block, means on the train for utilizing current from said rails to control the train, and means in both the adjoining blocks for controlling the supply of current to the rails of the train-occupied block.

3. A system of train control comprising: a track divided into insulated blocks, means controlled by the presence of a train in a block to supply current to the rails of a block, train controlling means, means on the train in bridging engagement with the rails normally held inoperative by current from said rails and operating upon the failure of the supply of current to actuate the train controlling means, and means in another block for preventing the supply of current to the rails of the train-occupied block.

4. A system of train control comprising: a track divided into insulated blocks, means controlled by the presence of a train in a block to supply current to the rails of a block, train controlling means, means on the train in bridging engagement with the rails normally held inoperative by current from said rails and operating upon the failure of the supply of current to actuate the train controlling means, and means in the block next in advance for preventing the supply of current to the rails of the train-occupied block.

5. A system of train control comprising: a track divided into insulated blocks, means controlled by the presence of a train in a block to supply current to the rails of a block, train controlling means, means on the train for short-circuiting the wheels and axles thereof normally held inoperative by current from said rails and operating upon the failure of the supply of current to actuate the train controlling means, and means in an-

other block for preventing the supply of current to the rails of the train-occupied block.

6. A system of train control comprising: a track divided into insulated blocks, means controlled by the presence of a train in a block to supply current to the rails of a block, train controlling means, means on the train for short-circuiting the wheels and axles thereof normally held inoperative by current from said rails and operating upon the failure of the supply of current to actuate the train controlling means, and means in the block next in advance for preventing the supply of current to the rails of the train-occupied block.

15. 7. A system of train control comprising: a track divided into insulated blocks, a circuit including the rails of a block, a track relay in said circuit affected by the presence of a train in the block, a second circuit including the rails of the block, a break in said second circuit adapted to be closed by the track relay upon the entrance of a train into the block to supply current to the rails having a different characteristic than that of the first-named circuit, and means on the train unaffected by current in the first-named circuit but responsive to the influence of the last-named current to control the train.

30. 8. A system of train control comprising: a track divided into insulated blocks, a circuit including the rails of a block, a track relay in said circuit affected by the presence of a train in the block, a second circuit including the rails of the block, a break in said second circuit adapted to be closed by the track relay upon the entrance of a train into the block to supply current to the rails having a different characteristic than that of the first-named circuit, and means on the train in bridging engagement with the rails for utilizing the last-named current to control the train.

45. 9. A system of train control comprising: a track divided into insulated blocks, a circuit including the rails of a block, a track relay in said circuit affected by the presence of a train in the block, a second circuit including the rails of the block, a break in said second circuit adapted to be closed by the track relay upon the entrance of a train into the block to supply current to the rails having a different characteristic than that of the first-named circuit, a second break in said second circuit adapted to be controlled by a track relay in the block in advance, and means on the train for utilizing the current of the second-named circuit to control the train.

60. 10. A system of train control comprising: a track divided into insulated blocks, an alternating current track circuit including the rails of each block, a track relay in said circuit affected by the presence of a train

in the block, a direct current circuit including the rails of the block, a break in the direct current circuit adapted to be closed by the track relay upon the entrance of a train into the block to supply current to the rails thereof, and means on the train for utilizing the direct current in said rails to control the train.

65. 11. A system of train control comprising: a track divided into insulated blocks, an alternating current track circuit including the rails of each block, a track relay in said circuit affected by the presence of a train in the block, a direct current circuit including the rails of the block, a break in the direct current circuit adapted to be closed by the track relay upon the entrance of a train into the block to supply current to the rails thereof, a second break in said direct current circuit adapted to be controlled by a track relay in the block in advance, and means on the train for utilizing the direct current in said rails to control the train.

70. 12. A system of train control comprising: a track divided into insulated blocks, means controlled by the presence of a train in a block to supply current to the rails of the block and to prevent the supply of current to the adjoining blocks upon the entrance of a train thereto, train controlling means, and train-carried means normally held inoperative by the influence of current from said rails and operating upon the failure of the supply of current to actuate the train controlling means to prevent the entrance of two trains into the same block.

75. 13. A system of train control comprising: a track divided into insulated blocks, a train, means for supplying current to the rails of a block in advance of a train passing through said block in either direction, means on the train for utilizing current from said rails to control the train and operating to stop the train upon the failure of the supply of current to the rails in advance of the train, and means controlled from the two adjoining blocks for cutting off the supply of current to the adjacent ends of the intervening block upon the entrance of trains into said blocks, whereby a train in the intervening block will be stopped upon the entrance of a train into the block which the train in the intervening block is approaching.

80. 14. A system of train control comprising: a track divided into insulated blocks, means for supplying current to the rails of a block in advance of a train passing through said block in either direction, a train, means on the train for utilizing current from said rails to control the train and operating to stop the train upon the failure of the supply of current to the rails in advance of the train, and means controlled from the block in advance for cutting off the supply of current to

a given block upon the entrance of a train into the advance block, whereby when two trains are approaching each other both trains will be stopped when either train enters the last intervening block.

15. A system of train control comprising: a track divided into insulated blocks, means for supplying current to both ends of the rails of a block, a train, means on the train for utilizing current from the rails in advance of the train to control the train and operating to stop the train upon the failure of the supply of current to the rails in advance of the train, and means controlled from the two adjoining blocks for cutting off the supply of current to the adjacent ends of the intervening block upon the entrance of trains into said blocks, whereby when two trains are running in the same direction the following train will be stopped upon entering the last intervening block while the train in advance will be unaffected.
16. A system of train control comprising: a track divided into insulated blocks, a normally closed track circuit including the rails of each block, a track relay for each block normally energized by current in said track circuit, a normally open train control circuit including the rails of each block and adapted to supply current having a different characteristic than that in the normally closed circuit, and a train carried controlling device responsive to the influence of the current supplied to the rails by the train control circuit, said train control circuit being controlled jointly by the relay in a given block and the relay in the block next in advance for supplying current to the rails of the given block to control the passage of a train therethrough.
17. A system of train control comprising: a track divided into insulated blocks, a normally closed track circuit including the rails of each block, a track relay for each block normally energized by current in said track circuit, a normally open train control circuit including the rails of each block and adapted to supply current having a different characteristic than that in the normally closed circuit, a train-carried controlling device responsive to the influence of the current supplied to the rails by the train control circuit, a break in said control circuit adapted to be closed when the relay in the same block is deenergized, and a break in said control circuit adapted to be closed when the relay of the block in advance is energized whereby current will be supplied to control a train passing through a given block when the block in advance is unoccupied.
18. A system of train control comprising: a track divided into insulated blocks, a normally closed track circuit including the rails of each block, a track relay at each end of each block normally energized by current in said track circuit, normally open train control

circuits connected to the rails at each end of each block, and adapted to supply current having a different characteristic than that supplied by the normally closed circuit, and a train-carried controlling device responsive to the influence of the current supplied by the train control circuits, each of said train control circuits being controlled jointly by a relay of the same block and a relay of an adjoining block for supplying current to the rails of a given block to control the passage of a train therethrough.

19. A system of train control comprising: a track divided into insulated blocks, a normally closed track circuit including the rails of each block, a track relay at each end of each block normally energized by current in said track circuit, normally open train control circuits connected to the rails at each end of each block and adapted to supply current having a different characteristic than that supplied by the normally closed circuit, and a train-carried controlling device responsive to the influence of the current supplied to the rails by the train control circuits, each of said control circuits having a break adapted to be closed by the relay in the same block when deenergized, each of said control circuits also having a break adapted to be closed by a relay in an adjoining block to supply current to control the passage of a train through a given block.

20. A train control system including: traffic rails arranged in blocks, two trackway sources of current for each block, each of said sources bridged across the traffic rails of a block, one of said sources to supply train governing current of a given character to the traffic rails of a block in series but normally disconnected from said rails, and the other of said sources to supply a control current, of a character different from that of the train governing current, to the traffic rails of a block in series, circuit means responsive to the control current to control the train governing current of another block and to connect the source of train governing current to the traffic rails of a block by the entry and traverse of a train in said block, a train, and automatic means on the train substantially continuously responsive to the influence of the train governing current flowing in the traffic rails of the block being traversed by the train but unresponsive to the control current flowing in said rails.

21. A system of train control comprising: a track divided into insulated blocks, means controlled by the presence of a train in a block to supply current to the rails of the block, means on the train responsive to the influence of the current in the rails to thereby control the train, and means in both the adjoining blocks for controlling the supply of current to the rails of the train-occupied block.

22. A system of train control comprising: a track divided into insulated blocks, a circuit including the rails of a block, a track relay in said circuit affected by the presence of a train in the block, a second circuit including the rails of the block, a break in said second circuit adapted to be closed by the track relay upon the entrance of a train into the block to supply current to the rails having a different characteristic than that of the first-named circuit, a second break in said second circuit adapted to be controlled by a track relay in the block in advance, and means on the train responsive to the current of the second-named circuit to thereby control the train.

23. A system of train control comprising: a track divided into insulated blocks, an alternating current track circuit including the rails of each block, a track relay in said circuit affected by the presence of a train in the block, a direct current including the rails of the block, a break in the direct current circuit adapted to be closed by the track relay upon the entrance of a train into the block to supply current to the rails thereof, and means on the train responsive to the influence of the direct current in said rails to thereby control the train.

24. A system of train control comprising: a track divided into insulated blocks, an alternating current track circuit including the rails of each block, a track relay in said circuit affected by the presence of a train in the blocks, a direct current circuit including the rails of the block, a break in the direct current circuit adapted to be closed by the track relay upon the entrance of a train into the block to supply current to the rails thereof, a second break in said direct current circuit adapted to be controlled by a track relay in the block in advance, and means on the train responsive to the influence of the direct current in said rails to thereby control the train.

25. A system of train control comprising: a track divided into insulated blocks, a train, means for supplying current to the rails of a block in advance of a train passing through said block in either direction, means on the train responsive to the influence of current in said rails and operating to control the train on the failure of the supply of current to the rails in advance of the train, and means controlled from the two adjoining blocks for cutting off the supply of current to the adjacent ends of the intervening block upon the entrance of trains into said blocks, whereby a train in the intervening block will be controlled upon the entrance of a train into the block which the train in the intervening block is approaching.

26. A system of train control comprising: a track divided into insulated blocks, means for supplying current to the rails of a block

in advance of a train passing through said block in either direction, a train, means on the train responsive to the influence of current in said rails and operating to control the train on the failure of the supply of current to the rails in advance of the train, and means controlled from the block in advance for cutting off the supply of current to a given block upon the entrance of a train into the advance block, whereby when two trains are approaching each other both trains will be controlled when either train enters the last intervening block.

27. A system of train control comprising: a track divided into insulated blocks, means for supplying current to both ends of the rails of a block, a train, means on the train responsive to the influence of current in said rails and operating to control the train on the failure of the supply of current to the rails in advance of the train, and means controlled from the two adjoining blocks for cutting off the supply of current to the adjacent ends of the intervening block upon the entrance of trains into said blocks, whereby when two trains are running in the same direction the following train will be controlled upon entering the last intervening block while the train in advance will be unaffected.

Signed at New York, in the county of New York and State of New York this 26th day of April, A. D. 1916.
